TABLE LIGHTER

Götz Florian Strzelcicky, Bad Homburg, Germany, assignor to Rowenta-Werke GmbH, Offenbach am Main, Germany

Filed Jan. 4, 1971, Ser. No. 103,952

Term of patent 14 years

Int. Cl. D27—05

U.S. Cl. D48—27

Fig. 1.

Fig. 2.

Fig. 5.

Fig. 3.

Fig. 4.

Fig. 6.

FIG. 1 is a perspective view of a table lighter showing my new design;

FIG. 2 is a side elevational view thereof;

FIG. 3 is a top plan view thereof;

FIG. 4 is a bottom plan view thereof;

FIG. 5 is an enlarged cross sectional view taken on line 5—5 of FIG. 2; and

FIG. 6 is a perspective view of a second embodiment of my design.

I claim:

The ornamental design for a table lighter, as shown and described.
